UNITED STATES PATENT OFFICE.

CLIFFORD A. M. WEBER, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

LUBRICATION SYSTEM.

1,238,367.

Specification of Letters Patent. Patented Aug. 28, 1917.

Application filed October 31, 1913. Serial No. 798,468.

To all whom it may concern:

Be it known that I, CLIFFORD A. M. WEBER, a citizen of the United States, and a resident of Edgewood Park, in the county 5 of Allegheny and State of Pennsylvania, have invented a new and useful Improvement in Lubrication Systems, of which the following is a specification.

My invention relates to lubricators, and 10 more particularly to that type embodying an oil cup located below the bearing and a wick for feeding the oil.

In some classes of apparatus, such, for example, as certain styles of fan blowers, the 15 oil cup is frequently located in such a position as to be more or less inaccessible, so that removal for the purpose of re-filling is difficult. One object of the present invention, therefore, is to provide a convenient means 20 for supplying oil to re-fill such cups without removing the same.

In other types of apparatus, such, for example, as reversible fans used for ventilation purposes, trouble has been experienced 25 with oil cups of the kind mentioned. When such fans are reversed so as to bring the oil cup on top, instead of below the bearing, the oil soon drains out, with the result that the journal runs dry and is damaged. 30 It is another object of the invention, therefore, to provide a lubricating system for reversible apparatus of this character, so designed that it will operate satisfactorily in either position.

35 In order that the invention may be readily understood, reference is had to the accompanying drawing, forming part of this specification, and in which,

Figure 1 is a vertical transverse section 40 through a journal and oil cup constructed in accordance with the first part of my invention, parts being shown in elevation;

Fig. 2 is a longitudinal section through the same, the wick and spring being omitted; 45 and,

Fig. 3 is an end elevation of a journal having lubricating apparatus arranged in accordance with the second part of my invention.

50 Referring to the drawing in detail, 1 designates the usual housing and 2 the bearing, while 3 indicates the shaft. The housing 1 is provided, at its under side, with the usual boss 1^a, that is internally screw-threaded to

receive the threaded end of an oil cup 4. 55 In this cup is located the usual wick 5 which projects through an opening 2^a in the bearing 2, and which is forced upwardly against the shaft by means of a spring 6. The upper end of this spring is wound tightly about 60 the wick and the lower end rests against the bottom of the oil cup. The parts so far described are of the usual construction.

My invention consists in the provision of means for supplying oil to the cup 4 without 65 removing the same. To this end, I provide an opening 8 in the housing 1 at a point opposite the boss 1^a, and I provide an oil passage extending from this opening to the opening into which the oil cup is screwed. 70 Such passage preferably consists of an annular groove 7 machined in the inner wall of the housing 1. An oil duct is thus formed by this groove in conjunction with the outer wall of the bearing 2. If desired, the groove 75 may be formed in the bearing instead of in the housing, the essence of the invention residing in locating such oil duct or channel between the housing and bearing. A tube 9, or other means for feeding oil, may be 80 screwed into the opening 8, if desired. It will be apparent that oil fed into this tube will flow around the outside of the bearing 2, through the groove or duct 7, and will thus find its way into the cup 4, from which it is 85 fed upward to the journal by the wick, as required.

Referring to Fig. 3, the construction is the same as in the other figures except that, in place of the tube 9, I provide a second oil cup 10, in all respects similar to the cup 4. To accommodate this cup 10, there is, of course, provided an additional boss 1^b, similar to the boss 1^a, and located diametrically opposite the same. In the position shown 90 in the drawing, the cup 4 contains the oil and the cup 10 is empty, the oil being fed upward from the cup 4 by the wick in the usual manner. If, now, the fan or other machine is inverted or reversed, so that the 95 cup 10 is brought underneath, while the cup 4 is on top, the oil will run from cup 4 through the duct 7, around the outside of the bearing into the cup 10, thus supplying oil which the wick in cup 10 can feed 100 to the journal.

It will be seen that this arrangement is perfectly reversible and operates equally

well in either position, the oil flowing from one cup to the other in accordance with the relative position of the cups. In this way, excessive supply of oil to the bearing and consequent waste thereof is prevented, and, at the same time, proper lubrication is always insured in either running position. It is thought that the many advantages of this simple and effective arrangement will 10 be readily appreciated without further explanation.

What I claim is:

1. The combination with a journal and a journal-box comprising the usual bearing and housing, of an oil cup carried by the housing at one side of the bearing, said housing having an oil hole formed therein at the opposite side of the bearing, and an oil duct located between said bearing and housing and serving to connect said oil hole with said cup.

2. The combination with a journal and a journal-box comprising the usual bearing and housing, of an oil cup carried by the housing at one side thereof, said housing having an oil hole formed therein at the opposite side thereof, one of said parts having a circumferential groove formed therein adjacent the other part, said groove constituting an oil duct extending from said hole to said cup.

3. The combination with a journal and a journal-box comprising the usual bearing and housing, of an oil cup carried by the housing at one side thereof, said housing having an oil hole at the opposite side thereof, and said housing also having a circumferential groove formed in the inner wall thereof, adjacent the bearing, said groove constituting a connection between said hole and cup.

4. The combination with a journal and a journal-box, of a separate oil cup carried by the said journal-box, an oil receptacle carried by the said journal-box and diametrically disposed with respect to the said oil cup and means for feeding oil from the said receptacle to the said cup.

5. The combination with a journal and a journal-box, of a pair of communicating oil cups carried thereby and located at diametrically opposite points thereof, whereby the lower of the two oil cups supplies the journal in any position of the said journal-box.

6. The combination with a journal and a journal-box provided with a pair of oil cups located at diametrically opposite points thereof, of means for feeding oil from one of said cups to the other, whereby the lower

of the two oil cups supplies the journal in 60 any position of the journal-box.

7. The combination with a journal and a journal-box, of a pair of oil cups carried by the said journal-box, one of said cups being located above and one below the journal, means for supplying oil from the lower cup to lubricate the journal, and means for feeding oil from the upper into the lower cup.

8. The combination with a journal and a journal-box comprising the usual bearing and housing, of a pair of oil cups carried by the housing, one above and one below the bearing, means for supplying oil from the lower cup to the inside of said bearing, and 75 means for feeding oil from the upper to the lower cup, outside of said bearing.

9. The combination with a journal and a journal-box comprising the usual bearing and housing, said bearing and housing having alined openings formed therein at opposite sides of the journal, an oil cup carried by said housing adjacent such alined openings at each side of the journal, a wick carried by each cup and projecting through 85 the respective alined openings so as to supply oil to the interior of the bearings, and a duct for feeding oil from one of said cups to the other.

10. The combination with a journal and a journal-box comprising a bearing and a housing, of an oil cup carried by the housing, and means for feeding oil from the cup to the journal, the said journal-box having an oil inlet and a passage leading therefrom 95 to the oil cup.

11. The combination with a journal and a journal-box, of a pair of communicating oil cups carried by the said journal-box and located at diametrically opposite points thereof, and means associated with the said oil cups for feeding oil to the said journal.

12. The combination with a journal and a journal-box comprising the usual bearing and housing, of a pair of oil cups carried by 105 the said housing, one above and one below the bearing; means associated with the said oil cups for supplying oil to the inside of the said bearing and further means for feeding oil between the said cups outside of the 110 said bearing.

In testimony whereof, I have hereunto subscribed my name this 16th day of Oct., 1913.

CLIFFORD A. M. WEBER.
